UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

DESIGN FOR AN ELECTRICAL-RECEPTACLE PLATE.

56,954.

Specification for Design.

Patented Jan. 18, 1921.

Application filed April 17, 1920. Serial No. 374,755. Term of patent 14 years.

To all whom it may concern:

Be it known that I, ERNEST CANTELO WHITE, a citizen of the United States, residing in the borough of the Bronx of the city of New York, in the State of New York, have invented a new, original, and ornamental Design for an Electrical-Receptacle Plate, of which the following is a specification, reference being had to the accompanying drawing, forming a part hereof.

The figure is a plan view of an electrical

receptacle plate showing my new design for the opening therein, the outer line of the preferred form of plate being shown in full lines and an alternative form of plate being shown in dotted lines.

I claim:

The ornamental design for an electrical receptacle plate, as shown.

This specification signed this 9th day of April, A. D. 1920.

ERNEST CANTELO WHITE.
